(57) **CLAIM**

We claim the ornamental design for a cable guide projection with boss, as shown and described.

DESCRIPTION

FIG. 1 is a top isometric view of the design for a cable guide projection with boss in accordance with a preferred embodiment of the present invention;

FIG. 2 is a bottom isometric view of the cable guide projection with boss of FIG. 1;

FIG. 3 is a top view of the cable guide projection with boss of FIG. 1;

FIG. 4 is a bottom view of the cable guide projection with boss of FIG. 1;

FIG. 5 is a front view of the cable guide projection with boss of FIG. 1;

FIG. 6 is a right side view of the cable guide projection with boss of FIG. 1; and,

FIG. 7 is a left side view of the cable guide projection with boss of FIG. 1.

The broken lines in the drawings represent the boundary of the claimed design and form no part of the claimed design.
